James L. Morris.

UNITED STATES PATENT OFFICE.

CHARLES LA DOW, OF ALBANY, NEW YORK.

SPRING-TOOTH SULKY-CULTIVATOR.

SPECIFICATION forming part of Letters Patent No. 269,069, dated December 12, 1882.

Application filed February 13, 1882. (No model.)

To all whom it may concern:

Be it known that I, CHARLES LA DOW, a citizen of the United States, residing in the city and county of Albany, and State of New York, have invented a new and useful Improvement in Spring-Tooth Sulky-Cultivators, of which the following is a specification.

This invention relates to that class of cultivators which employ spring-teeth for working soil; and it consists, first, in the combination of a rocking bar, a tooth-holder adapted to be clamped to the bar and held relatively thereto by frictional contact, and a spring-tooth clamped in a recess in the holder and sustained against upward strain by the upper portion of the holder; second, in the combination of a rocking bar, a spring-tooth, and a tooth-holder consisting of two parts clamped to the supporting-bar and held by frictional contact therewith, the upper part of the holder being provided with a rearward extension, which sustains the spring-tooth against undue upward pressure; third, in the combination of a draft-frame, ground-wheels, an axle rocking in the hubs of the wheels and carrying adjustable vibratory spring-teeth, a second bar carrying vibratory spring-teeth, and lever mechanism connecting the rocking-axle tooth-bar with the second bar to impart uniform movements thereto, the spring-teeth on both the axle and the bar being capable of adjustment in a direction around the same to vary the penetration of their points.

Referring to the drawings, Figure 1 represents a top view of my invention. Fig. 2 represents a side view of the same. Fig. 3 represents an end view of the tooth-bar, the manner of clamping the tooth-holder thereto, and also the manner of attaching the tooth to the holder. Fig. 4 represents a rear view of a section of a tooth-bar, showing the tooth-holder mounted thereon and the socket or recess in which the tooth is mounted in the holder. Fig. 5 represents a sectional side view, illustrating the manner of attaching the pole to the draft-frame and of varying the vertical position of said pole relatively to the frame.

The draft-frame of my invention consists of the four bars C C C C, to which are journalled, in suitable bearings, the axle or tooth bar B, and the tooth-bars B' B'.

b is a tooth holder or socket, which is ad-

justably secured to the tooth-bars by means of clamp-bolts, which permit the teeth to be set at any desired angle relatively to their bars, 55 and also to the adjacent series mounted on the other bars, and is also constructed to be moved laterally on the bar on which it is mounted, in order to arrange the teeth in groups, if desired, and in that manner make an opening between 60 the teeth, near the center of the machine, through which a row of plants may pass when it is desired to use the machine as a cultivator of rowed crops. This construction obviates the necessity for the removal of several teeth, 65 necessary to other machines, when used for such purpose, while the grouping of the teeth enables the machine to work the ground more thoroughly on each side of a row of plants than if the teeth should remain in their normal lateral position on the frame.

a a a are the spring-teeth, which are arranged in series or rows transversely across the line of draft, each series being mounted on its bar B or B'. The bars B' B' are each provided with a lever, x, clamped thereto in the same manner as the tooth-holders. The axle or bar B has a hand-lever, F, fastened thereto in the same manner as lever x to its bar B'. This bar F performs the same office to its bar B as do the levers x x to their bars B' B'. The levers x x and F are connected together by link n, so that when the lever F is rocked it moves the bar B through the line of the center of the wheel-hubs, the link n through its levers x x, 85 causing the bars B' B' to move in concert with the axle-bar. The teeth a a a are adjustably secured to the tooth-holder b by means of one of the clamping-bolts passing through the holder and the tooth. This tooth is fitted in a 90 recess in the holder, which prevents the tooth moving relatively to the holder. The upper jaw of the holder has an extension, c', which extension prevents the tooth from being unduly strained when passing over large obstructions.

The pole D is pivoted between the center bars, C C. To the forward end of each of said bars the stirrup T is pivoted. v is a bracket bolted securely to the pole. V is a crank-lever, 100 the vertical portion of which is provided with a threaded screw, which enters a corresponding screw or nut in the upper part of the stirrup T. The lower part of the lever V passes

through a hole formed in the bracket *v*. The lower part of said lever *V* is pierced with two holes—one above and one below the bracket *v*. These holes are each provided with a pin or key of ordinary construction, which allows the lever *V* to be turned freely in its threaded-screw bearings, carrying the pole with it, the lower pin in the lever *V* serving to lift the pole and the upper pin in said lever depressing it. 5 The stirrup *T* is pivoted to the pieces *C C* in order that it may remain at a uniform angle relatively to the pole during all of its vertical adjustment up and down.

10 The frames *C*, *B*, and *B'* are somewhat flexible, being journaled together by loose bearings, which permit the rocking of the bars *B'* within them. The braces *G G* are fastened to the pole *D* and to the frame *C C* to prevent the frame from being racked out of shape.

15 20 It will be observed that the arrangement of the levers *x x* and *F* with the link *n* and tooth-bars *B* and *B' B'* permit the teeth in all the series to be simultaneously varied, and the lever mechanism connected to the poles permits them all to be set at equal degrees of penetration at any desired depth, and without varying the vertical position of the tooth-bars themselves, and also allowing the axle to be utilized as a tooth-bar in this construction of my 25 invention. This arrangement of teeth and levers and adjustment of pole coat to produce not only a uniform penetration of all the teeth at any depth desired, but also a uniform vibration of all the teeth in each series. The 30 teeth in one series may be angularly adjusted relatively to the teeth in another either by loosening the lever *x* and turning the tooth-bar *B'* as desired, and retightening said lever *x*, or by loosening the tooth-holders themselves 35 40 and adjusting the teeth and holders relatively to their bar. These tooth-holders are adapted to be clamped to bars made of either wood, metal, or other material, and they may be constructed with teeth to bite into the surface of the bars; or they may be used smooth and held by friction only.

45 A tooth-rack, *R*, is fastened to the frame *C*, and adapted for engagement with the pawl *w* of the lever *F*. This pawl and rack will hold the teeth in any desired position as set.

50 The seat *S* is mounted on the machine in the usual manner.

t t are collars on the axle *B*, which serve to

keep the wheels *a a* at a proper distance from the end pieces, *C C*.

55 *t' t'* are collars which assist the teeth *a* in holding the pieces *C* from sliding laterally along the bars *B B'*, as described.

60 The rear tooth at the center of the machine may be removed from its socket when it is desired to group its adjacent teeth together to provide a passage or opening for a row of plants.

65 The lever *V* may be attached to the bracket *v* by means of collars or by a ball-and-socket joint.

70 75 I am aware that a harrow has been made with series of spring-teeth, which were simultaneously adjustable by means of lever mechanism, as shown in Letters Patent granted to A. J. Stewart, dated the 4th day of November, 1873, and numbered 144,236. Therefore I do not claim such an invention in its broadest sense.

Having described my invention, what I claim, and desire to secure by Letters Patent, 75 is—

1. The combination of a rocking bar, a tooth-holder adapted to be clamped to the bar and held relatively thereto by frictional contact, and a spring-tooth clamped in a recess in the 80 holder, and sustained against upward strain by the upper portion of the holder, substantially as described.

2. The combination of a rocking bar, a 85 spring-tooth, and a tooth-holder consisting of two parts clamped to the supporting-bar and held by frictional contact therewith, the upper part of the holder being provided with a rearward extension, which sustains the spring-tooth against undue upward pressure, 90 substantially as described.

3. The combination of a draft-frame, ground-wheels therefor, an axle rocking in the hubs of the wheels and carrying adjustable vibratory spring-teeth, a second bar carrying vibratory spring-teeth, and lever mechanism connecting the rocking axle-tooth bar with the second tooth-bar to impart uniform movements thereto, the spring-teeth on both the axle and the bar being capable of adjustment in a direction around the same to vary the penetration of their points, substantially as described. 95 100 CHARLES LA DOW.
